UNITED STATES PATENT OFFICE.

JACOB TAIZ, OF PHILADELPHIA, PENNSYLVANIA.

SHADE-ROLLER BRACKET.

1,114,203.

Specification of Letters Patent. Patented Oct. 20, 1914.

Application filed January 27, 1914. Serial No. 814,780.

To all whom it may concern:

Be it known that I, JACOB TAIZ, a subject of the Czar of Russia, residing at Philadelphia, in the county of Philadelphia and State of Pennsylvania, have invented certain new and useful Improvements in Shade-Roller Brackets, of which the following is a specification.

The object of my invention is to provide a supporting bracket for curtain poles and shade rollers, of novel, simple and efficient construction which may be readily applied to a window frame or other support without the aid of nails or screws and which may be readily adjusted to compensate for different lengths of poles or rollers to be supported thereby.

To this end my invented bracket consists of the elements thereof and the combinations of them as will be hereinafter fully described and particularly claimed.

In the accompanying drawings, illustrating my invention, Figure 1, is a front elevation of a portion of a window frame, showing a pair of my improved brackets applied thereto and a curtain supported by the brackets. Fig. 2, is a sectional plan of the parts shown in Fig. 1, as seen from the line 2—2 of Fig. 1. Fig. 3, is a view of one of the brackets detached from the window frame. Fig. 4, is an elevation of a modified form of the invention, and a portion of a frame having a glass panel, and to which the invention is applied. Fig. 5, is a sectional plan of the parts shown in Fig. 1, as seen from the line 5—5 of Fig. 4. Fig. 6, is a view of another modified form of the invention.

Referring to the drawings, 2 designates a portion of a window frame having the vertical grooves 3 therein to which the lower and inner sash 4 is slidably fitted. The inner wall of the groove 3 for the lower sash 4 is formed by the usual bar or rib 5; and my invention, as shown in Figs. 1, 2, 3 and 6, is adapted to be applied to this rib 5.

The body portion of my improved bracket, as shown in Figs. 1, 2 and 3 comprises a pair of parallel arms 6 and 7 connected by a part 8, the arm 6 having upper and lower outwardly-projecting flanges 9 and the whole being preferably formed of sheet metal bent into the structure illustrated. The flanges 9 have openings 10 therein, and in the outer wall of each open-

ing 10 is formed a plurality of spaced sockets 11, the sockets of one flange being in vertical alinement with the sockets of the other flange. Between the flanges 9 is a vertically arranged plate-like lever 12 having oppositely extending fulcrum projections 13 which extend into the openings 10 and are adapted to seat in any two vertically alined sockets 11 in the flanges 9. 60 The inner portion of the lever 12 is off-set, at 14, from the fulcrum projections 13 and the off-set portion 14 is provided with inwardly projecting teeth 15 which are adapted to move toward the arm 7 and 65 embed themselves in the structure to which the bracket is applied when the lever 12 is moved on its fulcrum projections 13 from the dotted line position to the full line position shown in Fig. 2. The outer portion 70 of the lever 12 is provided with an opening 16 therein which receives the projection on the adjacent end of the curtain roller.

In Figs. 1 and 2, I have shown two of my improved brackets applied to the window frame and a shade roller 17 extending between and carried by the brackets. The two brackets are alike in every particular except that they are made right and left so that the body of one bracket may embrace the rib 5 on one side of the window frame and that the body of the other bracket may embrace the rib 5 on the other side of the window frame; and except that one lever 12 has a perforation therein to 80 receive the pivot projection on one end of the shade roller and the other lever 12 has a slot therein to receive the flat projection on the other end of the shade roller, the flat projection being connected to the spring 85 within the roller 17 in the usual manner. The connections between the ends of the roller and the levers 12 are the same as is common and well known in connection with spring shade rollers. When the two 90 brackets are applied to the ribs 5, the levers 12 are first moved on their fulcrums toward each other to the dotted line position to bring the projecting teeth 15 outwardly of the inner faces of the arms 6, thus permitting 95 the brackets to be slipped around the ribs 5 in the positions shown; and, thereafter the levers 12 are moved on their fulcrums 13 away from each other to the positions shown by full lines causing the teeth 15 110 to be forced into the ribs 5 and thereby securing the brackets to the ribs. After the

levers have been moved to the positions shown by full lines the shade roller 17 is engaged therewith and the shade roller prevents the levers 12 from moving toward each other and consequently prevents the loosening of the brackets from the ribs 5. When it is desired to remove the brackets, the roller 17 is first removed from the levers 12, the outer end of the levers are then moved on their fulcrums toward each other to disengage the teeth 15 from the ribs 5, and the brackets are then moved toward each other from the ribs 5. By engaging the fulcrum projections 13 of the levers 12 with different vertically alined sockets 11 the levers 12 may be adjusted toward or from each other to fit shade rollers of different lengths within limits. As the brackets are located near the top of the window frame, and as the lower sash 4 is rarely if ever raised that high, it matters not that the arms 7 extend into the grooves 3.

In the modification shown in Figs. 4 and 5 I provide the lever 12 with a vertical pin 17' in lieu of the fulcrum projections 13 and I provide the arm 6 of the body portion of the bracket with a projection 18 having projecting teeth 19, as shown. This structure is adapted to be applied to such structures as window sashes and doors having glass panels therein. When applied to such structures, the lever 12 is first moved on its fulcrum to bring the teeth 15 outwardly of the inner face of the arm 6 to the dotted line position. The teeth 19 are then engaged with the strip 20 adjacent to the glass panel 21 in the frame 22. The arm 6 is then engaged with the face of the frame 22 and the lever 12 is moved to the full line position, causing the teeth 19 to embed themselves in the strip 20 and the teeth 15 to embed themselves in the frame 22 and thus hold the bracket in place.

In the modification shown in Fig. 6, the arms 6 and 7 and part 8 are retained and in lieu of the lever 12 and its connection with the arm 6, the arm 6 has a projection 23 at right angles to the arm 7, and fulcrumed on the projection 23, at 24, is a lever 25. The inner portion of the lever 25 is provided with teeth 26 and the lever is adapted to be forced inwardly to embed the teeth 26 in the rib 5 when the bracket is applied thereto and the outer portion of the lever pressed down after first being raised to move the teeth 26 outwardly of the inner face of the arm 6. A spring 27 is provided and secured to the lever 25 and bears against the arm 6 to force the outer end of the lever 25 normally down. The outer portion of the lever 25 is provided with a suitable opening 28 to receive the projecting end on the shade roller.

I claim:

65 1. In a bracket for the purpose described,

a body portion having a part adapted to engage one part of a supporting structure, a lever fulcrumed on the body portion and having a part movable toward the first named part and adapted to engage another part of said supporting structure when the lever is moved on its fulcrum, and roller supporting means on the lever. 70

2. In a bracket for the purpose described, a body portion having a part adapted to engage one part of a supporting structure and having a plurality of spaced sockets therein, a lever having a fulcrum portion adapted to engage in any of said sockets and having a part movable toward the first named part 80 and adapted to engage another part of said supporting structure when the lever is moved on its fulcrum, and roller supporting means on the lever. 75

3. In a bracket for the purpose described, a body portion having a part adapted to engage one part of a supporting structure and having upper and lower projecting flanges, a lever between and fulcrumed on said flanges and having a part movable toward the first named part and adapted to engage another part of said supporting structure when the lever is moved on its fulcrum, and roller supporting means on the lever. 85

4. In a bracket for the purpose described, a body portion having a part adapted to engage one part of a supporting structure and having upper and lower projecting flanges, each of said flanges having a plurality of spaced sockets therein and the sockets of one flange being alined with the sockets of the other flange, a lever between said flanges and having oppositely extending fulcrum projections adapted to engage any alined sockets in said flanges and having a part movable toward the first named part and adapted to engage another part of said supporting structure when the lever is moved on its fulcrum, and roller supporting means on the lever. 95 100 105

5. In a bracket for the purpose described, a body portion having two substantially parallel arms and a part connecting them, a lever fulcrumed on one of said arms and having a part movable toward the other of said arms when said lever is moved on its fulcrum, and roller supporting means on the lever. 110 115

6. In a bracket for the purpose described, a body portion having two substantially parallel arms and a part connecting them, one of said arms having upper and lower projecting flanges, a lever between and fulcrumed on said flanges and having a part movable toward the other of said arms when the lever is moved on its fulcrum, and roller supporting means on the lever. 120 125

7. In a bracket for the purpose described, a body portion having two substantially parallel arms and a part connecting them, 130

one of said arms having upper and lower projecting flanges, each of said flanges having a plurality of spaced sockets therein and the sockets of one flange being alined with 5 the sockets of the other flange, a lever between said flanges and having oppositely extending fulcrum projections adapted to engage any alined sockets in said flanges and having a part movable toward the other 10 of said arms when the lever is moved on its fulcrum, and roller supporting means on the lever.

8. In a bracket for the purpose described, a body portion having a part adapted to engage 15 one part of a supporting structure, a

plate-like lever fulcrumed on the body portion and having a part off-set from its fulcrum and provided with projecting teeth movable toward and from the first named part and adapted to engage another part of 20 said supporting structure when the lever is moved on its fulcrum, and roller supporting means on the lever.

In testimony whereof I affix my signature in presence of two witnesses.

JACOB TAIZ.
